— I — . —

FIG. 1 is a top view of a hydrofoil vehicle embodying the design of our invention;

FIG. 2 is a side elevation view of the hydrofoil vehicle;

FIG. 3 is a front side elevation view of the hydrofoil vehicle;

FIG. 4 is a bottom view of the hydrofoil vehicle;

FIG. 5 is a side elevation view of the hydrofoil vehicle, showing the side opposite to that of FIG. 2; and

FIG. 6 is a rear view of the hydrofoil vehicle.

We claim:

The ornamental design for a hydrofoil vehicle, substantially as shown and described.
